SOUND SIGNAL

Robert M. Critchfield, Anderson, Ind., assignor,
by mesne assignments, to General Motors Corporation, Detroit, Mich., a corporation of Delaware

Application February 23, 1933, Serial No. 658,034

7 Claims. (Cl. 177—7)

This invention relates to improvements in sound signals and more particularly to mounting means for such devices.

It is among the objects of the present invention to provide a sound signal with a resilient mounting means which substantially prevents vibrations of the sound signal from being transmitted to the member supporting it, or vibrations or shocks of the supporting member being transmitted to the sound signal.

Another object of the invention is to improve the appearance of an outside mounted signal device.

Further objects and advantages of the present invention will be apparent from the following description, reference being had to the accompanying drawings wherein a preferred embodiment of one form of the present invention is clearly shown.

20 In the drawings:

Fig. 1 is a fragmentary front view of a motor vehicle illustrating a plurality of sound signals mounted on the outside thereof.

Fig. 2 is a longitudinal sectional view of a sound signal constructed and arranged in conformity with this invention.

Fig. 3 is a sectional view taken on the line 3—3 of Fig. 2.

Fig. 4 is a sectional view taken on the line 4—4 of Fig. 3.

Fig. 5 is a view, partly in side elevation and partly in section, of a sound signal and a modified form of a supporting post.

35 Figs. 6 and 7 are sectional views taken on the lines 6—6 and 7—7 of Figs. 5 and 6 respectively.

Fig. 8 is a view partly in elevation and partly in section of a sound signal and another modified form of a supporting member.

40 Figs. 9 and 10 are sectional views taken on lines 9—9 and 10—10 of Figs. 8 and 9 respectively.

With particular references to the drawings, Fig. 1 illustrates a portion of a motor vehicle showing the usual fenders 21 supporting posts 45 or brackets 22, employed on many makes of automobiles. The upper end of the posts 22 being provided with securing means (not shown) for supporting the head lamps 23 in proper position. Preferably the posts 22 are hollow, as shown in Fig. 2, to provide an enclosure for a portion of lead wires, one of which is shown at 24, having one end connected to a terminal (not shown) of the signal device and the other end connected with a source of current. Each post 55 22 is provided with a transverse aperture 25

through which a projector or trumpet 26 of a sound signal 27 protrudes and is attached to a collar 31.

The sound signal 27 comprises a mounting plate 30 to which is secured the collar 31 by screw devices 32 to rigidly secure a diaphragm 33 at its peripheral edge 34. The central portion of the mounting plate 30 is apertured, the metal being punched out of the bottom and bent up to provide a bracket 35 having a portion 36. 10 Upon the portion 36 there is secured at one end a blade spring 37, which extends toward the center of the base and parallel with the mounting plate 30, and the circuit controller mechanism of the motor unit is insulatingly mounted upon 15 this bracket 37 in substantial parallel relation with the blade spring 37.

The circuit controller mechanism comprises a leaf spring 38 provided with a movable contact 39 which cooperates with an adjustable contact 40 carried by a rigid bracket 41 in substantial alignment with the movable contact 39. These contact supporting elements are secured to the bracket 35 by screws 42. The end of the leaf spring 38 is disposed in the path of an insulating washer adjacent to an actuating nut 43. Both the insulating washer and nut are carried by an armature rod 44 reciprocable through a central aperture 45 of a field frame 46.

Reciprocable movement of the armature rod 30 44 is accomplished by securing one end of the rod 44 to the free end of the blade 37 and the other end extending through the diaphragm 33 and spacing washers 47 and 48. The washers 47 and 48 and the diaphragm 33 are clamped 35 against a shoulder 49 of the rod by a nut 50 threadedly engaging the rod. The rod 44 terminates within the sound chamber defined by the collar 31. On the threaded extension of the rod there is mounted a piston disc 51 which is 40 secured in place by a nut 52.

An armature 60 is carried by the rod 44 adjacent the free end of the spring 37, the armature being maintained in normal position by the tension of the spring 37 and diaphragm 33. The 45 armature is actuated by an electro-magnet device comprising the field frame 46 which is adjustably supported in any suitable manner on the mounting plate 30. The field frame comprises a plurality of E-shaped magnetic plates riveted 50 together to form parallel grooves 62 and 63 into which a field winding 64 is adapted to be placed.

In operation of this sound signal energization of the field frame or electro-magnet unit attracts 55 the armature 60 against the effect of the spring

37 and diaphragm 33. The armature is thereby moved toward the field frame 46 and flexes the diaphragm toward the trumpet 26 and carries the disc with it. This movement of the armature 5 will cause the contact carrying member 38 to be flexed, and in doing so the nut 43 will move the contact 39 away from the contact 40 whereupon the field coil will be de-energized and permit the spring 37 and diaphragm 33 to return to normal 10 position again closing the contacts 39 and 40 which reconditions the parts for the cycle movement stated above.

The motor mechanism is protected by a cup-shaped cover having its peripheral edge fitting 15 about an annular recess provided by the collar 31. The cover is retained in position upon the collar 31 by a screw threaded into a channeled yoke. The yoke is secured at each end (not shown) by several of the screw devices 32 to the 20 mounting plate 31.

In the illustrated embodiment of the sound signal device, the trumpet or projector 26 is secured to a collar 70 provided with a threaded portion 71 cooperating with a threaded central aperture of the collar 31 so as to hold the trumpet 25 in the desired position upon the collar. The collar 31 is provided with a reduced threaded portion 75 and a key 76 to form a shoulder 77. The reduced portion receives spring blades or 30 laminations 78 having aligned apertures and recesses or notches corresponding to the contour of the threaded and key portions on the reduced portion 71 of the collar 31. The key 76 operates to prevent the sound signal from turning relative 35 to the laminations 78. The laminations are secured to the collar 31 by a clamping nut 79 of desired form and threaded upon the threaded portion 75 and run up against the laminations so as to hold the laminations firmly against the shoulder 77 in the proper position upon the collar 31.

For the purpose of resiliently supporting the sound signal so as to permit full sound producing 45 vibrations of the sound signal, yet substantially preventing such vibrations from being transmitted from the sound signal to its supporting device, or any vibrations of the supporting device from being transmitted to the sound signal, materially 50 to effect the efficient operation of the sound signal, the lamination ends are attached to the post 22 substantially at right angles to the axis of the sounding device and secured to the post by a clamp 80 and screws 81 or any other suitable 55 means. This connection is such, that the direction of the movements of the laminations are substantially parallel to the direction of the sound waves. It will be noted that the clamp 80 and post are dished out or offset as at 82 and 83 respectively, so that only the outer edges of the 60 laminations rest adjacent the post and clamp so as not to restrain the movement of the laminations.

Before assembling the projector to the collar 31, the collar 70 is provided with a flange 84 at 65 one end. A rubber bushing 85 having a flange 86 is placed within the aperture 25 of the post 22 and the collar 70 is passed through the rubber bushing 85 so that the flange 86 will be interposed between the flange 84 and against the 70 surface of the post which provides acoustical insulation tending to absorb noise producing vibrations to which the projector might be subjected and thus prevent this amplification by the hollow post.

75 In Figs. 5, 6, and 7, certain modifications are

illustrated, but in main the structure is essentially the same. In the modified form, the post 22a, upon which the signal device is mounted, is solid. In this form, the post 22a is provided with a transverse opening 25a through which a collar 70a together with the projector 26 is located within the opening 25a. The flange 84a of a collar 70a bears against the end surface of the reduced portion of the collar 31.

In Figs. 8, 9, and 10 another modification of 10 mounting the sound signal is illustrated. In this form, a bracket 90 is provided with an aperture 91 to support the sound signal in somewhat the same manner as disclosed by the other forms described. When the sound signal is mounted, as 15 shown in Figs. 8, 9, and 10, the laminations 77a and one arm of the bracket 90 are held in spaced relation by a spacer 93. The spacer is secured to the bracket by screws 94 and the laminations 77a are held firmly against the spacer 93 by a pair 20 of clamps 95 having flat surfaces 96 to receive the flat ends 97 of the laminations 77a. The clamps 95 are secured to the bracket 90 by screw devices 98 whereby the laminations 77a are prevented from turning relative to the spacer. This supporting bracket 90 may be attached to any suitable 25 part of the motor vehicle.

It will be noted that the spring blades or laminations in each modification are substantially parallel with the support so that said laminations, 30 if vibrating at all, will tend to vibrate about the axis of the sound signal and not in counter-direction.

The resilient mounting means is of simple structure and design and one that will improve the out- 35 side mountings of a sound signal, and said means will substantially prevent the vibratory energy of the sound signal from being partly absorbed by the vehicle so as to maintain as near as possible the true sounds produced by the sound signal. 40

While the form of embodiment of the present invention as herein disclosed, constitutes a preferred form, it is to be understood that other forms might be adopted, all coming within the scope of the claims which follow. 45

What is claimed is as follows:

1. A signal device comprising in combination; a casing; a sound producing diaphragm supported by the casing; an electromagnet for operating the diaphragm; a projector attached to the casing; a support having an aperture through which the projector extends; a plurality of leaf spring members provided with apertures intermediate their ends to receive a portion of the casing; means for securing the casing to the intermediate portion of the spring members; and means for attaching the ends of the spring members upon the support so that the free portion of the spring members will cause the casing and the projector to move along the axis of the aperture in the support when the signal device is actuated.

2. A signal device comprising in combination; a casing; a sound producing diaphragm supported by the casing; an electromagnet for operating the diaphragm; a projector attached to the casing; a support having an aperture through which the projector extends; resilient members having openings intermediate their ends to receive a portion of the casing; means for securing the casing to the intermediate portions of the resilient members; and means for attaching the ends of the resilient members upon the support to move the projector and the casing substantially along the axis of the aperture in the support when the signal device is actuated.

3. A support for a signal device, comprising in combination; a housing; a plurality of superimposed leaf springs having openings to receive a portion of the housing; means for securing the springs to the housing; a projector adapted to be connected with the housing; a support having a transverse opening; means for securing the ends of the springs to the support in such a manner that the axis of the casing and the projector substantially coincides with the axis of the aperture in the support, and the resilient movements of the free portions of the springs will oscillate the casing and the projector along the axis of the aperture when the signal device is actuated.
4. In a signaling device having a casing member provided with a tubular extension, the combination comprising; a plurality of superimposed springs provided with openings intermediate their ends to receive the tubular extension; means for connecting the intermediate portion of the springs to the tubular extension; a support provided with a transverse opening; a hollow member protruding through the opening and coupled with the tubular extension; and means to secure the ends of the springs to the support in such a manner that the resilient movements of the free portions of the spring will move the hollow member substantially along the axis of the transverse opening of the support when the signaling device is actuated.
5. In a signaling device having a casing member provided with a reduced tubular portion; the combination comprising; a resilient member provided with an opening intermediate its ends to receive the reduced tubular portion; a nut having screw threaded engagement with the reduced tubular portion for securing the intermediate portion of the spring to the casing; a hollow member adapted to be coupled with the reduced tubular portion; a pair of brackets; means for connecting the brackets and the ends of the spring to the support but on opposite sides of the opening of the support so that the axis of the hollow member substantially coincides with the axis of the aperture.
6. A support for a sound signal having a sound producing member, comprising in combination; a casing for enclosing the sound producing member; a standard having an opening; a projector extending through the opening and connected with the casing; a resilient member; means for connecting the casing to the intermediate portion of the resilient member; and means for connecting the ends of the resilient member to the standard in such a manner that the resilient movement of the free portions of the resilient member is directed substantially along the axis of the aperture in the standard, such supporting means substantially preventing the projector and casing from engaging the standard when the sound signal is actuated.
7. A support for a signal device having a sound producing member, comprising in combination; a casing; a support having a transverse opening; spacing means secured to the support; a spring having its intermediate portion secured to the casing; a projector adapted to extend through the opening and connected with the casing; a pair of brackets; and screw-threaded fastening means securing the brackets to the support to clamp the ends of the spring between the brackets and the spacing means in such a manner that the axis of the projector is substantially in alignment with the axis of the opening and that the resilient movement of the spring takes place substantially at right angles to the axis of the transverse opening.

ROBERT M. CRITCHFIELD.
